UNITED STATES PATENT OFFICE.

WILLIAM G. KENDALL, OF NEWARK, NEW JERSEY.

HINGE FOR VANITY-CASES.

1,225,439.

Specification of Letters Patent.

Patented May 8, 1917.

Application filed January 25, 1917. Serial No. 144,508.

To all whom it may concern:

Be it known that I, WILLIAM G. KENDALL, a citizen of the United States, residing at Newark, in the county of Essex and State 5 of New Jersey, have invented certain new and useful Improvements in Hinges for Vanity-Cases, of which the following is a specification.

My present invention relates to new and 10 useful improvements in boxes and more particularly in hinge constructions for connecting boxes and covers, the primary object of my invention being the provision of an improved form of hinge for vanity boxes, al- 15 though I do not intend to limit its use to such containers.

Vanity boxes as now constructed usually include a body and cover, each stamped from sheet metal, the two being connected 20 by a hinge in which the hinge leaves may be integral with the boxes and covers and connected by a pintle pin or in which hinge leaves connected by a pintle pin may be riveted or otherwise secured to the box and 25 cover. In the manufacture of vanity boxes cheapness of construction is a prime essential and at the same time all parts must be efficient and durable. A hinge construction necessitating the use of pintle pins or the 30 employment of rivets or similar fastening devices is very expensive, when considered in relation to the total expense of the box, and the primary object of this invention resides in the construction of a hinge which 35 shall employ neither pintle pins nor separate fastening devices.

A further object of my invention consists 40 in the construction of a hinge of such a character that the box and cover may be readily assembled.

With these and other objects in view, my invention will be more fully described, illustrated in the accompanying drawings, and then specifically pointed out in the claims 45 which are attached to and form a part of this application.

In the drawings:

Figure 1 is a perspective view of a conventional vanity box constructed with a 50 hinge made in accordance with my inven-

tion, the cover being shown in open position;

Fig. 2 is a central vertical sectional view of the box with the cover open, the cover being shown in elevation to clearly bring 55 out the construction and positioning of the hinge;

Fig. 3 is an unassembled fragmentary perspective view of a box and cover provided with my improved hinge, a somewhat modified form of hinge construction being here shown;

Fig. 4 is a perspective view of the hinge employed in the construction shown in Fig. 3.

Corresponding and like parts are referred to in the following description and indicated in all the views of the drawings by the same reference characters.

In order to insure a clear and accurate 70 understanding of my invention, I have illustrated it in connection with a conventional form of vanity box 10 stamped or otherwise formed from sheet metal and preferably cylindrical in shape. This box includes a bot- 75 tom 11 and upstanding peripheral wall 12 which, intermediate its height, is preferably formed with an annular outstruck stop bead 13. Coöperating with this box is a cover 14 having a depending annular flange 15 80 adapted to engage about the upper edge of the box and to abut against the stop bead 13 when the cover is closed. This flange may be outstruck at one point, as shown at 16, to facilitate opening. A wedging ring 17 85 may secure a mirror 18 against the inner face of the cover, if desired. These features, however, form no part of my present invention.

The peripheral wall 12 of the box is pro- 90 vided with a horizontal slot 19, either in or immediately above the bead 13 and the peripheral flange of the cover 14 is formed, preferably at a point opposite the outstruck portion 16, with a depending ear 20 forming 95 a hinge member, as will be apparent. The free end of this ear is bent to lie in a plane at right angles to the remainder of the ear and adjacent portion of the flange 15 and is provided immediately adjacent its end and 100

at each side with laterally directed locking tongues 21 which are bent inwardly somewhat, as shown in Fig. 1, in order that the portion of the ear carrying them may rest 5 evenly against the inner face of the marginal wall of the box when the cover is in open position. The ear is also formed with a cleft 22 extending transversely of the ear from the inner portion of the base of one of 10 the tongues, as clearly shown in Fig. 2 of the drawings. The manner of providing this cleft will be more fully described in connection with the form of hinge shown in Figs. 3 and 4.

15 Obviously, the ear being slidable in the slot 19 and being bent intermediate its length so that its free end portion extends at right angles to the remaining portion forms an efficient hinge connection between 20 the cover and box, while the tongues projecting from the ear prevent any disengagement of the cover and box.

In Figs. 3 and 4, I have illustrated a box and hinge construction which is identical 25 with that shown in Figs. 1 and 2, except that the hinge proper is in the form of a plate 23 of sheet metal which is attachable to the flange of the cover and which takes the place of the hinge ear 20. This plate is 30 bent intermediate its length so that its terminals lie in planes at right angles to each other and the body portion of the plate is formed with a number of U or V-shaped clefts defining tongues 24 which are passed 35 outwardly through slots formed in the flange 15 of the box cover and rebent to secure the hinge plate thereto. The opposite end of the ear is provided with a laterally directed tongue 25 corresponding to one of the 40 tongues 21 and at its opposite side with a tongue 26 corresponding to the other tongue 21 but projecting at right angles to the tongue 25 and in effect forming a reduced continuation of the ear. The side edge of 45 the ear adjacent the base of this latter tongue 26 is provided with a V-shaped notch 27 of such depth and width that the tongue 26 may be bent to extend laterally from the ear and directly away from the tongue 25. When so bent, it will be obvious that 50 the tongues 25 and 26 of the form shown in Figs. 3 and 4 will exactly correspond to the tongues 21 of the form first described and that the notch will have been closed so as 55 to merely show a cleft corresponding to the cleft 22. As a matter of fact, the integral ear 20, of the form shown in Figs. 1 and 2, is originally stamped out with the tongues and notch exactly corresponding to the 60 tongues and notch of the hinge plate 23 but the parts in Figs. 1 and 2 are shown in the position which they occupy when the hinge has been applied, while in Fig. 3 the parts

are in the position which they occupy before assemblage.

65 Aside from the securing of the hinge plate 23 to the flange of the cover, the assemblage of the box with either the integrally formed or separately formed hinge is the same. The tongue 25 or that tongue 21 more remote from the notch is passed inwardly through the slot 19 of the box so as to project beyond one end of the slot when the cover is twisted to swing the tongue 26 through the slot so that the body portion of 70 the hinge plate or ear may be passed through the slot. The tongue 26 is then bent to extend in alignment with the tongue 25, as shown in Figs. 1 and 2 of the drawings, to permanently lock the box and cover together. 75

This form of hinge may be economically manufactured as a single stamping process suffices to strike out both the blank for the cover and hinge from the sheet metal, the hinge ear being formed from a portion of 80 the sheet metal which would otherwise be waste or scrap. Furthermore, the box may be readily assembled with this hinge and no separable parts, such as pintle pins, rivets or the like, are required.

90 It will of course be understood that I reserve the right to make any changes, within the scope of the appended claims, without in the slightest degree departing from the spirit of my invention.

95 Having thus described the invention, what is claimed as new is:

1. In a hinge construction, the combination with two members to be hinged, one being formed with a slot, of a hinge ear projecting from the other, a tongue projecting laterally from the ear at its free end, and a second tongue projecting forwardly from the free end of the ear at that side opposite the first tongue, the ear at the base of the 100 second tongue being formed in its side edge with a notch whereby the second tongue may be swung to align with the first.

105 2. In a hinge construction, the combination with a receptacle having an upstanding wall formed adjacent its free edge with a horizontal slot and a cover having a depending flange to engage about the wall, of a hinge ear projecting from the flange and substantially equal in width to the width of the slot, said hinge ear having its free end portion bent to extend at substantially 110 right angles to its body portion, an anchoring tongue extending laterally from the free end of the ear at one side, and an anchoring 115 tongue extending beyond the free end of the ear and in the direction of the ear at the free side, such side of the ear being notched whereby after the first tongue has been passed through the slot of the box wall and 120 the ear swung to pass its free end through 125

the slot after the first tongue, the second tongue may be bent to aline with and extending in a direction opposite to the first tongue while still lying in the plane of the 5 free end of the ear.

3. In a hinge construction, a hinge ear, a tongue projecting laterally from one side of the ear at its free end, and a second tongue projecting in the direction of and beyond

the ear at its free end and adjacent the opposite side of the ear, the ear at the base of the second tongue being formed in its side edge with a notch whereby the second tongue may be swung to extend in alinement with the first. 10

In testimony whereof I affix my signature. 15

WILLIAM G. KENDALL. [L. s.]
